UNITED STATES PATENT OFFICE.

FRANKLIN W. BROOKS, OF NEW YORK, N. Y., ASSIGNOR OF ONE-FOURTH
TO WM. C. MCINTIRE, OF WASHINGTON, D. C.

CRAYON OR LEAD HOLDER.

SPECIFICATION forming part of Letters Patent No. 267,970, dated November 21, 1882.

Application filed October 20, 1882. (No model.)

To all whom it may concern:

Be it known that I, FRANKLIN W. BROOKS, a citizen of the United States, residing at New York city, New York, have invented new and useful Improvements in Crayon and Lead Holders, of which the following is a specification.

My invention relates to certain new and useful improvements in crayon or lead holders; and it consists in the peculiarities of construction and operation hereinafter more fully described and specifically claimed.

In the accompanying drawings, Figure 1 represents a plan view of a holder embodying my invention; Fig. 2, a central longitudinal section at the line *x x* of Fig. 1; Fig. 3, a plan view of the central tube, with the thimble-head portion in section; and Fig. 4, a cross-section taken at the line *y y* of Fig. 2.

Similar letters indicate like parts in the several figures.

A represents the wooden barrel, cored axially to receive the crayon-containing tube B, which is formed at its upper end with a thimble-shaped head, C, having an annular flange, 5 *a*, projecting slightly beyond the holder A, and milled or roughened to facilitate turning the same. This head C having the outwardly-projecting flange *a* enables it to be grasped and operated whether the eraser be present or not, and is designed to subserve the special purpose of operating in a specified way the internally-arranged crayon-tube. The head or upper end of the case is bored out, of course, to receive the thimble portion C. The tube B is 10 introduced in the direction indicated by the arrow at Fig. 1, and is held against retraction by a short screw or pin, *b*, passing through the case or holder A, and projecting slightly into a short slot, *d*, Fig. 3, in the upper end of the 15 tube B. The formation of the slot *d* is such that it not only prevents retraction of the tube, but at the same time permits a limited rotation of the same, for the purpose presently explained. This arrangement is necessary in order that the tongue *e* and cam *f* shall 20 always be held in proper relation to produce the required results. The tube B near its lower end is formed with a spring-tongue, *e*, the point of which is turned inwardly, as seen 25 at Fig. 2, and which may be slightly rough-

ened. The purpose of this tongue *e* is to grasp and hold the lead when desired, which it is caused to do by a partial rotation of the tube B, through the medium of the roughened flange *a* of the thimble-head C. The central bore of the case A is enlarged near the point end, as seen at D, and is formed with a projecting cam, *f*, adapted to impinge upon the outer surface of the spring-tongue, which at the point of contact is preferably built up by a round teat, *g*, 30 Fig. 3. The cam is so constructed with reference to the tongue *e* that about a quarter-turn of the tube B will be sufficient to force the tongue *e* inward a sufficient distance to firmly grasp the lead F within the tube. A return movement of the tube B will obviously release the tongue *e*, and its spring capacity will cause it to move away from the lead and permit the latter to slide freely within the tube. Any suitable spring mechanism may be connected 35 to the tube B to automatically rotate it to the position necessary to force the tongue *e* inwardly, so that after it has been positively released to permit the lead to be projected a suitable distance beyond the point of the case, 40 or entirely concealed within the same, the tongue will be automatically operated to prevent further movement of the lead. This spring for actuating the tube B, as just described, is not an absolute necessity, as it may 45 be operated entirely by hand. The tongue *e* is formed in one side of the lead-tube, a suitable distance from or above the point or tip, and so that the latter is left unbroken to give a 50 complete circumferential support to the projecting lead; and the tongue *e*, being arranged in one side of the tube, as described, also operates in such manner as to compress the lead against the opposite continuous surface of the tube, thus getting a long bearing against the 55 lead, and avoiding the tendency existing in the ordinary split or double-jawed tubes of pinching or biting the lead, or weakening it at the point where it should have the greatest 60 tenacity.

E is a lead-sharpener and eraser, adapted 65 to be removably located within the thimble-head C, so that the sharpener may be used to point the lead by entirely removing same from its seat, or the eraser may be concealed and 70

100

protected, as shown. I do not, however, lay claim to this construction in this case, but refer for a more particular description of the same to another case filed simultaneously.

5 In introducing the tube B, it will be readily observed the spring-tongue *e*, being forced inward, easily passes through the more contracted portion of the central bore of the case A, and when reaching the portion D it naturally springs outward. The tongue may be integral with the tube, or made separately and secured thereto by a rivet or otherwise.

What I claim as new, and desire to secure by Letters Patent, is—

15 1. In a lead or crayon holder, the tube B, adapted to be partially rotated and having in one side only a spring-tongue, *e*, above the tip

or end of the tube, in combination with the case A and cam *f* formed therein, whereby the lead is held at a point above or inside 20 the tip, substantially as described.

2. The combination and arrangement, with the case A, having hollow head, and cam *f*, of the crayon-tube B, provided with tongue *e*, and thimble-head C, having projecting flange 25 *a*, substantially as described.

In testimony whereof I have hereunto set my hand in the presence of two subscribing witnesses.

FRANKLIN W. BROOKS.
